UNITED STATES PATENT OFFICE.

WALLACE V. CALLENDER, OF CHICAGO, ILLINOIS.

ATTACHMENT FOR LADIES' HATS.

1,275,219.

Specification of Letters Patent. Patented Aug. 13, 1918.

Application filed July 23, 1917. Serial No. 182,113.

To all whom it may concern:

Be it known that I, WALLACE V. CALLENDER, a citizen of the United States, residing at Chicago, in the county of Cook and State 5 of Illinois, have invented a new and useful Attachment for Ladies' Hats, of which the following is a specification.

This invention relates to an attachment for ladies' hats, and is intended to be secured 10 by sewing or otherwise upon the inside thereof, out of sight, and to serve as a guide for the usual hat-pins employed as a means for securing the hat to the hair.

The employment of hat-pins by ladies as 15 a means for holding their hats upon their heads is now almost universal, such means being convenient as well as ornamental, but one very great disadvantage results, namely: the crown or sides of the hat soon becomes 20 disfigured as well as materially injured by the clusters of unsightly pin-holes where the pins make their entrance and exit. The holes made by the entrance of the pin may be avoided provided the wearer will exercise 25 care in entering the pin in the same hole before putting on the hat, but when once on the head and the pin started through the hair it is all guess-work as to the point where the pin will emerge or make its exit. 30 The result is always the same—the formation of a disfiguring cluster of pin-holes which in time ruin the hat as well as the trimmings.

This invention has for its principal object 35 the avoidance of clusters of unsightly pin-holes in the sides of the hat and its trimming and the reduction of such pin-holes to but two—where the pin makes its entrance and exit—regardless of the number 40 of times the pin is inserted; or, in other words, to provide means whereby the hat-pin is caused to always emerge from the hat at the same point or through the same pin-hole.

45 The invention consists in a thin plate of preferably metal and tapered toward one end, at least, at which point it is provided with an aperture forming a pin-passage or hole, and in narrow marginal flanges converging toward the tapered end of the plate and thereby forming guides leading to the aperture, the plate being bent or curved longitudinally so as to approximate the curvature of the crown of the hat and therefore 50 lie snugly and flatly against the same and offer no obstruction whatever.

Other though minor objects of the invention will hereinafter appear, and the novel features of the invention will be particularly pointed out in the claims.

60

Referring to the drawing:

Figure 1 illustrates my invention in operative position upon the inside of a hat, the latter being broken away and together with the pin shown in dotted lines;

65

Fig. 2 is an enlarged detail in plan of the invention;

Fig. 3 is a sectional view on the line 3—3 of Fig. 2;

Fig. 4 is a plan view of a second form of 70 such attachment;

Fig. 5 is a similar view of yet another form; and

Fig. 6 is a transverse sectional view on the line 6—6 of Fig. 5.

75

Similar numerals of reference indicate similar parts in all the figures of the drawing.

As will be apparent, the hereinafter described device may be made of a variety of 80 materials the only essential being that such be of sufficient hardness to guide the advance end of the hat-pin and not permit of penetration thereby. Very thin light metal, however, is preferred, though the invention 85 is not to be understood as being limited in this respect.

In the example of my invention illustrated in Figs. 1, 2 and 3 of the drawing, 90 1 designates a thin metal plate, reduced or pointed at one end, at the extremity of which is formed a small perforation 3. The opposite end of the plate may be given any shape desired, much depending upon what other uses the device is put to, but in the 95 present instance, said opposite end is semi-circular.

In the forms shown by the figures of the drawing referred to, the entire plate is surrounded by a very narrow flange 2, which 100 following the contour of the margin of the plate, combined at the sides thereof to produce converging flanges that lead to the small hole or perforation 3.

Viewed in longitudinal section (see Fig. 105 3) the plate 1, it will be observed, is slightly curved so that it may approximate somewhat the curvature of the crown of the hat and when in position lie flat against the inside thereof. Any means may be employed 110 for securing the plate in position, but I prefer stitching 5, for which purpose the plate

may be provided at convenient points along its margin with perforations 4, for the passage of the needle.

The attachment is secured inside and at 5 the back of the hat, the conical end of the plate being disposed in the direction of the travel of the hat-pin. The wearer, before placing the hat upon her head, first introduces the hat-pin through the hole in the 10 crown of the hat, the same hole being used each time, places the hat upon her head and proceeds to force the pin through the hair.

After passing through the hair, the advance end of the pin comes in contact at some 15 point with the plate 1 and is deflected to one side or the other and therefore into contact with one of the guides formed by the narrow flange 2, the flange serving to guide the point or advance end of the pin to the opening or hole 3, from which it emerges and passes on through the hat. As the pin is 20 always guided to the hole 3 and passes therethrough it follows that it must always emerge from the same pin-hole in the hat, 25 so that but the one pin-hole results instead of the usual cluster.

Some ladies prefer to employ two pins, the same being passed in opposite directions through the hair and hat. To meet 30 this want, I may form the curved plate 1 with tapered or reduced opposite ends, each of the latter having a pin-passage formed by a perforation or hole 3, and the marginal flange 2 conforming to the contour of the 35 plate will form opposite pairs of converging guides.

While Figs. 1 to 4 illustrate the preferred form of the invention, that is, wherein the marginal flange is employed, yet I may omit 40 the flange, and, as illustrated in Figs. 5 and 6, substitute as a guiding means for the advance end of the pin any form of guiding groove 6, the latter flaring at the end of the plate opposite the opening 3 and converging 45 toward said opening. However, the flange

is very narrow and its presence is hardly noticeable and offer no obstruction likely to engage the hair during the operation of putting the hat on or off.

Where the attachment is made up cheaply, 50 its surface may be utilized as a means of advertising by having the name of the milliner embossed or otherwise appearing thereon, or where made up more expensively the 55 surface may be utilized for monograms, names, &c.

Having described my invention, what I claim, is:

1. An attachment for ladies' hats for the purpose described, the same consisting of a 60 plate smooth upon its reverse side and curved longitudinally to fit the curvature of the hat-crown and adapted when in position to lie snugly thereagainst throughout its 65 length, said plate being tapered toward one end and provided at said end with an aperture forming a passage for a hat-pin, and with marginal flanges at opposite sides of 70 said plate converging and leading to said aperture and forming guides for the pin, and attaching means for the plate.

2. An attachment for ladies' hats for the purpose described, the same consisting of a plate smooth upon its reverse side and curved longitudinally to fit the curvature of the hat-crown and adapted when in position to lie snugly thereagainst throughout its 75 length, said plate being tapered toward its opposite ends and provided at each of said ends with an aperture forming a passage for 80 a hat-pin, and with marginal flanges at opposite sides of said plate converging and leading to said apertures and forming guides for the pin, and attaching means for the plate.

WALLACE V. CALLENDER.
